DESIGN FOR A COMBINED ASH TRAY AND PLAYING CARD RECEPTACLE

Marion S. de Sarro, New York, N. Y.

Application September 25, 1945, Serial No. 122,339

Term of patent 14 years

(Cl. D34—5)

To all whom it may concern:

Be it known that I, Marion S. de Sarro, a citizen of the United States, residing at New York, in the county of New York and State of New York, have invented a new, original and ornamental Design for a Combined Ash Tray and Playing Card Receptacle, of which the following is a specification, reference being had to the accompanying drawing, forming part thereof.

Figure 1 is a side perspective view of a combined ash tray and playing card receptacle, showing my new design.

Figure 2 is a side fragmentary elevation showing the depth and contour of the ash tray.

I claim:

The ornamental design for a combined ash tray and playing card receptacle, as shown.

MARION S. DE SARRO.
